Primary Examiner — Sandra Snapp*Assistant Examiner* — Donald B Rose, Jr.(74) *Attorney, Agent, or Firm* — Daryl R. Wright; Greg Carr(57) **CLAIM**

We claim the ornamental design for a model vehicle body, as shown and described.

DESCRIPTION

FIG. 1 is an upper, left, front perspective view of a model vehicle body;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an upper, left, front perspective environmental use view of a model vehicle body.

In the drawings, the broken lines showing features of the model vehicle body form no part of the claimed design.

The broken lines in FIG. 8 depict environmental subject matter that form no part of the claimed design.

1 Claim, 6 Drawing Sheets(56)
